UNITED STATES PATENT OFFICE.

JOHN BRYANT, OF LAKE CITY, FLORIDA.

WARDROBE-BUREAU.

No. 889,175.

Specification of Letters Patent.

Patented May 26, 1908.

Application filed July 27, 1906. Serial No. 328,099.

To all whom it may concern:

Be it known that I, JOHN BRYANT, a citizen of the United States, residing at Lake City, in the county of Columbia, State of Florida, have invented certain new and useful Improvements in Wardrobe - Bureaus; and I do hereby declare the following to be a full, clear, and exact description of the invention, such as will enable others skilled in the art to which it appertains to make and use the same.

This invention relates to wardrobe bureaus; and it consists in the construction and arrangement of parts defined in the claim.

In the accompanying drawings,—Figure 1 is a front elevation of a wardrobe bureau constructed in accordance with this invention, and showing the curtain in its raised, or inoperative position. Fig. 2 is a similar view, but with the curtain lowered. Fig. 3 is a side elevation. Fig. 4 is an enlarged detail perspective view of the writing desk shelf. Fig. 5 is a transverse horizontal section taken through the upper compartment of the bureau, with the door in its closed position.

Corresponding parts are designated by similar reference numerals in the several views.

Referring to the drawings, the bureau is shown as having a large upper compartment 10, lower compartments 11 and 12, and a drawer 13 intermediate the said lower compartments. The upper compartment is lined, as shown at 10', with any desired material.

The compartment 11 contains a shelf 14, slidably mounted therein and composed of a pair of sections hinged together on their upper faces, so as to fold one upon the other, when not in use. Said shelf slides in grooves formed on the inner faces of the bureau sides and extending from their rear edges to near their front edges, there being a laterally extending stop 14' on each side of said shelf 45 and traveling in said grooves, to prevent said shelf from being entirely withdrawn. The upper face of the shelf may, if desired, have a covering not shown, of any desired material. The lower compartment 12 contains a shelf 15, slidably mounted therein, and adapted to form a support for books. The upper shelf 14 is adapted for use, when extended, as a writing desk, and to one side of the bureau is attached a rack 16, provided with supports

17 for pens or pencils, and with a shelf 18 having a circular seat 19 therein, to retain an ink-stand. Rack 16 is likewise provided with a lower shelf 20 for paper and envelops. As shown in Figs. 2 and 3, said rack is placed upon the bureau side approximately in line 60 with the writing desk, so that a person making use of the latter may easily reach the necessary stationery from the rack.

The bureau is provided with a door 21 hinged to the opposite side thereof, and carrying on its inner face a mirror 22, extending practically the entire length of said door. The upper compartment is provided with a series of small hooks 23, attached to the upper portion thereof for carrying such small 70 articles as scissors, buttonhooks, and the like, while the rear wall of said compartment carries larger hooks 24, for supporting bonnets, collars, neckties, etc. 25 designates a rack formed of material similar to that with 75 which said compartment is lined, and provided with a plurality of pockets for the reception of combs, hair brushes, etc. Located above said rack is a pin-cushion 26. Said compartment is likewise provided with 80 a pair of trays 27, at opposite sides thereof, for pins, buttons, or jewelry,

Attached to the top of the bureau is a curtain 28 of dust-proof material, provided at its lower end with a roller 29, upon which 85 said curtain is wound, when in its inoperative position, and held in place upon the top of the bureau by means of straps 30. When the curtain is unrolled, it will obviously cover the front of the bureau, when the door 90 is open, and will prevent all dust and dirt from entering into the upper compartment, the curtain being retained in such position by catches 31, attached to the bureau sides and fitting over the extended ends of the 95 roller. The bureau likewise carries upon the outer face of one of its sides a towel supporting rod 32 carried by the notched upper portions of the sides of a shelf 33, secured in any way to the bureau, said shelf forming a support 100 for clothes brushes, and the like.

What is claimed, is:—

A bureau provided with compartments in the interior thereof, the side walls of one of said compartments having guide grooves 105 formed therein and extending from the rear edges to near the front edges thereof, and an extensible shelf slidable within said grooved

compartment for use as a writing desk, said shelf comprising a pair of sections hinged together at their inner ends and adapted to be folded one upon the other when the shelf is in its inoperative position within said compartment, the intersection of said shelf having lateral extensions formed on opposite sides thereof adjacent its rear end and adapted to

travel in said grooves, to limit the outward movement of the shelf.

In testimony whereof, I affix my signature, in presence of two witnesses.

JOHN BRYANT
